UNITED STATES PATENT OFFICE

167,217

DOLL

Idell M. Matthews, Westport, Conn.

Application July 31, 1951, Serial No. 16,087

Term of patent 7 years

(Cl. D34—4)

To all whom it may concern:

Be it known that I, Idell M. Matthews, a citizen of the United States, residing at Westport, county of Fairfield, and State of Connecticut, have invented a new, original, and ornamental Design for a Doll, of which the following is a specification, reference being had to the accompanying drawing, forming part thereof.

Fig. 2 is a side view thereof.

I claim:

The ornamental design for a doll, as shown.

IDEELL M. MATTHEWS.
